Ernst Hutzler, New York, N. Y.

Application May 13, 1958, Serial No. 50,862

Term of patent 14 years

(Cl. D34—15)

The single figure is a perspective view of a figure toy or a similar article, showing my new design, the opposite side, not shown, being substantially a mirror image thereof.

The present application is a continuation-in-part of my copending application Serial No. D. 44,340, filed on December 27, 1956, now abandoned.

I claim:

The ornamental design for a figure toy or similar article, as shown and described.
